PISTON EXPANDER

Walter J. Six, Indianapolis, Ind.

Original application October 10, 1932, Serial No. 637,032. Divided and this application October 8, 1934, Serial No. 747,405.

14 Claims. (Cl. 309—12)

This invention relates to expanding means for skirts of pistons adapted for use in engines, such as internal combustion engines, compression engines, steam engines and the like, being a division 5 of my copending application Serial No. 637,032, filed October 10, 1932, entitled Piston expander.

It is usual to provide such pistons with a head and a skirt which is partially or wholly separated from the head by a circumferential opening or 10 openings. The lands between the ring grooves on the head are usually made slightly smaller in diameter than the diameter of the skirt which is formed initially to closely fit the interior of the cylinder. The skirt particularly when formed of aluminum 15 or similar metal, is usually slotted longitudinally to permit the skirt to expand and contract so that it will closely follow the cylinder wall. However, due to wear of the cylinder and the piston, this 20 closeness of fit between the skirt and the cylinder wall is soon destroyed with the attendant results of "piston slap" undue leakage of the oil past the piston rings, and decreased efficiency of the engine. In order to overcome these defects without reborning the cylinders or replacing the pistons, it has 25 been heretofore suggested that spring means of some sort within the skirt be provided to expand the skirt.

The principal object of my invention is to provide an improved and simple expander which exerts an expansive action substantially about the entire skirt while permitting the skirt to contract when necessary in operation, and thereby attain a more perfect fit between the worn skirt and the cylinder wall than has been possible heretofore.

The invention resides in a compressible spring expander adapted to be compressed within a worn piston to exert outward pressure against the skirt. More particularly, it relates to expanders of simple form having a plurality of downwardly extending folds which may form in effect a split wall adapted to engage and bear against the inner surface of the piston skirt over a substantial area to force it radially outward to conform to a worn 45 or out-of-round cylinder. For this purpose, a pair of oppositely disposed expanding portions or wall sections bear against the slotted portion of the skirt and that portion opposite thereto, while another pair of wall sections engage and press 50 outwardly against the opposed boss portions, to expand the circumferential length of the skirt.

The full nature of the invention will be more clearly understood from the accompanying drawing and the following description and claims:

55 Fig. 1 is a central vertical section through a

piston with the expander mounted therein. Fig. 2 is a plan view of the under side of the piston showing the expander therein. Fig. 3 is a perspective view of the expander removed from the piston.

In the drawing there is shown a piston of the usual type having a head 10, piston ring grooves 11, a peripheral slot 12 partially separating the head from the skirt 13, and inwardly extending projections in the form of piston pin bosses 14 10 through which piston pin 15 extends.

Said skirt is provided with the usual substantially longitudinal slot 12a extending from the lower end to the peripheral slot 12 on one side thereof intermediate the bosses, to permit of expansion and contraction to conform to the cylinder in which it operates.

For yieldingly expanding said skirt and imparting thereto a radial outward force under spring tension, there is provided an expander 20 as illustrated in Fig. 3. Said spring is substantially "cup-like", being adapted to be forced in inverted position upwardly within the piston skirt toward the head so that the downwardly extending expanding portions or wall sections 25 bear against the inner surface or side walls of the split skirt of the piston.

To permit of the flexing of the expander under pressure, it may be described as having a bight portion 16 adapted to lie adjacent the piston head. Extending downwardly from said bight portion, there are a pair of wall sections or resilient portions 17 curved to conform with the curvature of the piston skirt and adapted to be forced inwardly against the inherent spring tension 35 therein when mounted within the skirt so as to normally exert an outward pressure thereupon. Intermediate said portions 17, there are oppositely disposed wall sections 18, which are so arranged as to engage the bosses 14 to normally exert an 40 outward pressure against said bosses and the corresponding side of the skirt.

Said sections 18 extend downwardly about said bosses to embrace the same as shown in Fig. 1. The expander embodies suitable expansion folds 45 or expandible formations 20 separating the corresponding wall sections 17 and 18 to permit them to flex relative to each other under spring tension.

From the foregoing, it will be observed that 50 wherein a piston having a split skirt is caused to operate in an enlarged cylinder or an out-of-round cylinder, or wherein said piston has lost its normal inherent expanding force, the installation of said expander therein will cause the 55

- skirt to spread so as to accommodate it to the cylinder in which it operates, while permitting of contraction owing to the longitudinal slot therein and the yielding character of the expander.
- It will also be noted that by reason of the cup-shaped integral formation of the expander, it may be readily inserted in the piston and driven home therein without the requirement of unusual tools. While the invention has been herein described as applied to the standard type of split piston, it is also applicable to other types of piston including the so-called T-slot type.
- The invention claimed is:
1. In combination with a piston having a slotted skirt, piston pin bosses and a piston pin, a cup-shaped spring expander comprising a continuous wall extending downwardly substantially at right angles to the piston pin and contacting with and exerting pressure against said bosses, said expander also contacting with and exerting pressure against the piston skirt intermediate the bosses, and expansible formations spaced around the periphery thereof.
  2. In combination with a piston having a skirt with a slot, piston pin bosses and a piston pin, a cup-shaped expander formed of a single piece of spring metal having a pressure exerting wall, said wall being generally oblong in cross section and provided with curved expansible formations, said wall engaging said bosses and also the piston skirt on either side of and adjacent to said slot, and having openings through which the piston pin extends.
  3. A cup-shaped piston skirt expander formed of a single piece of spring metal to provide a side wall portion of generally oblong shape, said wall portion being continuous and having spaced inwardly extending expansible formations formed therein.
  4. In combination with a piston having a skirt, a piston pin and piston pin bosses, a cup-shaped skirt expander formed of spring metal, a continuous flexible wall disposed between the bosses and extending into engagement with the skirt between said bosses, said wall having openings through which said piston pin extends.
  5. In combination with a piston having a skirt with a slot, piston pin bosses and a piston pin carried by said bosses, a cup-shaped skirt expander having a continuous yieldable pressure exerting wall through which the piston pin projects and which engages the bosses and engages the skirt on each side of said slot.
  6. In combination with a piston having a split skirt and piston pin bosses adapted to receive a piston pin, a cup-shaped spring metal expander having a side wall portion generally oblong in shape and adapted to engage and press against said bosses, the ends of the expander side wall being adapted to engage and press against the piston skirt intermediate said bosses and on the opposite sides of the split of the skirt, each side of the expander having expansible formations, and also openings adjacent the boss-engaging portions of the expander side wall to accommodate the piston pin.
  7. An expander adapted to be inserted within the skirt of a piston, said expander being formed of spring metal forming a continuous wall generally oblong in shape and having spaced portions adapted to engage the piston skirt, said wall also having a plurality of inwardly looped expansible formations spaced thereabout.
  8. In combination with a piston having a split skirt, piston pin bosses, an expander formed of spring metal forming a continuous wall generally oblong in shape and having opposite portions thereof contacting with the piston skirt intermediate the pin bosses, the expander having inwardly extending reverse expansion folds adjacent its contacting portions.
  9. In combination with a piston having a split skirt and piston pin bosses, a spring metal expander having a continuous wall portion generally oblong in shape and having substantially parallel sides, the ends of the wall portion being adapted to engage the piston skirt intermediate said bosses, each side of the wall portion having yieldable formations between said bosses and said ends of the expander.
  10. In combination with a piston having a split skirt and piston pin bosses, a one-piece integral spring metal expander having a continuous wall portion generally oblong in shape and having substantially parallel sides adapted to press against said bosses, the ends of the expander being adapted to engage and press against the piston skirt intermediate said bosses, and each side of the expander having vertically extending expandible formations adjacent the engaging ends of the expander.
  11. A one-piece piston skirt expander formed of spring metal and forming a continuous integral oblong figure having a plurality of spaced apart expansion folds adjacent each end.
  12. In combination with a piston having a split skirt and piston pin bosses, an expander formed of spring metal and generally oblong in shape and having parallel sides adapted to press against said bosses, the ends of the expander being adapted to engage the piston skirt intermediate the bosses and each side of the expander having vertical yielding formations adjacent the pin bosses.
  13. A one-piece piston skirt expander formed of spring metal and forming a continuous oblong figure having a substantially vertical yielding formation therein.
  14. The combination with a piston having a split skirt and piston pin bosses, of a continuous expander formed of spring metal and generally oblong in shape and having parallel sides adapted to press against said bosses, the ends of the expander being adapted to engage the piston skirt intermediate the bosses, and a substantially vertical yielding formation provided in said expander for permitting contraction thereof.
